UNITED STATES PATENT OFFICE

ROBERT W. GOFF, OF SCHENECTADY, NEW YORK, ASSIGNOR TO GENERAL ELECTRIC COMPANY, A CORPORATION OF NEW YORK

CIRCUIT CONTROLLER

Application filed February 10, 1927. Serial No. 167,281.

The invention relates to circuit controllers, particularly those having contacts operable with a time delay action and it provides improvements that are of special advantage in 5 automatic time element multiple point starters for electric motors or other similar devices.

As applied to motor starters of the above character the invention provides improved 10 means for operating a plurality of motor accelerating contacts in a timed sequence after closure of the line switch. Furthermore, the sequential operation of the several accelerating contactors and the motor 15 line switch may be accomplished by means of a single electromagnet preferably operated with an excessive initial energization under start and stop push button control. While the sequential operation of the several 20 motor accelerating contacts is retarded by a common time delay mechanism such, for example, as a gear escapement device, the armature or plunger of the operating electromagnet itself is arranged to be operated 25 instantaneously to the attracted position, thereby effectively avoiding a prolonged excessive current input that might overheat the electromagnet during the sequential operation of the accelerating contactors under the control of the time delay 30 mechanism.

Moreover, the improved time element motor starting circuit controlling mechanism of the present invention readily permits 35 dynamic braking and also full field starting of the motor to be effected in the proper timed sequence, if desired, all with a relatively compact, simple, and inexpensive operating and circuit controlling mechanism. In addition, the motor starting mechanism is so 40 constructed as to materially facilitate installation and maintenance under practically all service conditions. In this connection the improved manner of mounting the motor 45 starter mechanism in an enclosing casing to allow ready removal for inspection and necessary repair, as well as the ease of making connections with the motor and the supply line are features of practical utility.

50 The accompanying drawings illustrate an

automatic time delay multiple point motor starter embodying the improvements of the present invention in a preferred form. Fig. 1 is a perspective view showing the general assembly of the motor starting mechanism in 55 its enclosing casing with the cover removed. Fig. 2 is a side view showing more in detail the construction of the multiple contacts for controlling the motor circuits together with the common operating electro- 60 magnet therefor as well as the common time delay escapement mechanism. Figs. 3, 4, 5 and 6 are simplified perspective views illustrating the relative positions of the multiple contact circuit controlling mechanism during 65 different phases of operation. Fig. 7 is a connection diagram of a motor control system embodying the motor starting mechanism illustrated in the preceding figures.

Referring to Fig. 1, it will be seen that the 70 entire motor starter mechanism is enclosed within a casing 10 having a removable cover 11 and both the casing and cover are provided with suitable ventilating openings as indicated. The panel or base 12, upon which 75 all of the operating and circuit controlling elements and the time delay mechanism are mounted, is removably secured within the casing 10 by means of the two screws 13 and 14. As shown in Fig. 2, the starting and 80 dynamic braking resistors R_1 and R_2 are suitably mounted on the back of the panel 12.

The motor circuit controlling switch mechanism comprises the double throw motor line and dynamic braking switch contact 15, the 85 motor accelerating switch contacts 16 and 17, and the motor field regulating contact 18. The contact 19 is employed to reduce automatically the initial excessive energization of the operating electromagnet 20 in a manner 90 that will be pointed out more fully in connection with the operation of the motor control system, diagrammatically illustrated in Fig. 7.

The movable magnetic member or armature 21 of the operating electromagnet is top connected through the parallel arms 22 and the links 23 to the contact operating member 24 which is in the form of a plate provided 95 with a suitable bent over arm for connection 100

with the links 23 and with bent over lugs for pivotally mounting upon the shaft 25, as more clearly shown in Figs. 3 to 6. The shaft 25 is mounted in suitable supports 25', extending from the base 12, as shown in Fig. 2. The double throw motor line and dynamic braking switch 15 is directly mounted upon the switch operating member 24 and is held in yielding engagement therewith by the biasing spring 26 and the readily removable locking key 27.

The motor accelerating contacts 16 and 17, however, are mounted in staggered relation upon a separately operable retarding member 28 which also is in the form of a plate having bent-over lugs for pivotally mounting upon shaft 25 in overlapping relation with the member 24. The retarding member 28 has a downwardly extending arm 29 connected to the rotatable gear escapement time delay mechanism 30 through the agency of the curved rack gear 31 and ratchet pinion 32 which have cooperating teeth formed to engage only when the arm 29 is swung out from the panel. The contacts 16 and 17 are biased into engagement with the retarding member 28 by the biasing springs 33 and 34 and cooperating locking keys 35 and 36 respectively. The bent-over lug 28a of the retarding member holds the contact 17 slightly out of alignment with the contact 16 to insure successive operation of contacts 16 and 17 as will appear hereinafter. It, however, should be noted that the locking keys 35 and 36 pass through suitable openings in the retarding member 28 and are locked into engagement with the operating member 24 at their rear ends, as shown in Fig. 2. With this arrangement, as will be pointed out in detail hereinafter, the gear escapement mechanism 30 serves to retard operation of the retarding member 28 while permitting instantaneous operation of the operating member 24 by the electromagnet, thereby setting up a strain in the biasing springs 33 and 34 tending to cause the member 28 to follow member 24 and thereby carry the accelerating contacts 16 and 17 into successive abutting engagement with the cooperating stationary contacts 16' and 17'.

The field regulating switch 18 which is rotatably mounted in the stationary support 37 is biased to the circuit closing position by the spring 38. The insulating finger 39 for operating the field switch 18 is mounted upon the retarding member 28 and yieldingly connected to the operating member 24 by biasing spring 40 and locking key 41 in exactly the same manner as the two motor accelerating contacts 16 and 17 just described. The electromagnet controlling switch 19, however, is operated by the insulating finger 42 which is fixedly secured to the contact operating member 24. Switch 19 is of the

double throw type and is biased into engagement with its upper cooperating stationary contact and out of engagement with the lower resilient stationary contact by the biasing spring 43.

The terminal clips 44 are provided for receiving a thermal overload relay protective device T indicated diagrammatically in Fig. 7 preferably of the cartridge type, such for example as shown in Getchell Patent 1,581,192, although obviously any other suitable form of overload protective device may be employed with the motor starter if desired. A braking relay 45 is mounted on the panel 12 beside the operating electromagnet 20 and is connected as shown in Fig. 7 to prevent energization of electromagnet 20 until the braking current decreases below a certain value.

As shown in detail in Fig. 2, the gear escapement time delay mechanism 30 comprises a suitable casing within which the gear wheel 50 is mounted upon the shaft of the ratchet pinion 32 in mesh with the small driving pinion 51 of the escapement gear 52. The pendulum timing pawl 53 having adjustable pendulum weights 54 cooperates with the escapement gear 52 to effect closure of the accelerating contacts 16 and 17 and operation of the field switch 18 in a timed sequence after closure of the motor line switch 15.

The precise arrangement of the circuit controlling mechanism of the motor starter may be more readily perceived by reference to the simplified views shown in Figs. 3 to 6. The various circuit connections controlled thereby, as shown in Fig. 7, and the function of the various operating and controlling elements of the motor starter may be better understood from the description of the operation thereof which is as follows:

In Fig. 7 the circuit controlling mechanism is shown connected to control the operation of the motor M of the usual type having a shunt field winding and a commutating field winding under the remote control of the Start and Stop master switch push buttons indicated. The resistors R₁ and R₂ serve during starting of motor M as accelerating resistors under the control of the accelerating contacts 16 and 17 and during stopping of motor M as braking resistors in the closed circuit established about the motor armature upon opening of the upper line contact of switch 15 and closure of the lower dynamic braking contact thereof. The adjustable resistor R₃ for the motor field circuit is controlled by the field regulating switch 18 to insure full field starting of the motor and reduced field running operation thereof. The operating electromagnet controlling switch 19 is connected with the start and stop push buttons to insure a strong initial energization of the operating electromagnet 20 and a materially reduced energization there-

after. The thermal overload device T functions in a well known manner to interrupt the circuit of electromagnet 20 upon the occurrence of an excessive current flow from the supply lines 60 to the motor circuit.

As illustrated in Fig. 7 the motor starting mechanism is in the full running position, in which current is supplied to the motor M from the supply lines 60 with resistors R₁ and R₂ in the motor circuit shunted and a selected portion of the adjustable field regulating resistor R₃ inserted in circuit with the shunt field of the motor. The motor armature circuit may be traced from the upper supply line 60 through the disconnecting switch 61, the terminal plate 46, the commutating field and armature of motor M, conductor 62 thence through the accelerating contact 17, the conductor 63, the line switch 15, the heating winding of the thermal relay T, and the disconnecting switch 61 to the lower supply line 60. The shunt field circuit extends directly from the terminal plate 46 through the shunt field, and the portion of resistor R₃ determined by the position of the adjustable contacts 64 to the heating winding of the thermal overload relay.

Under these conditions the motor controlling switches are maintained in their respective position shown in Fig. 7 due to energization of the operating electromagnet 20 through a circuit extending through the contact of the thermal relay T, the contact of the braking relay 45, the entire winding of the operating electromagnet, conductor 65, the lower contact of switch 19 and the stop push button, to the terminal 46. Likewise, the motor is operating at its selected reduced field speed.

To stop the motor, the stop push button is operated, thereby deenergizing the electromagnet 20 and permitting the armature 21 thereof to fall and open the motor line switch 15 before opening the motor accelerating switches 16 and 17. This results from the fact that the upturned finger 24a engages the line switch 15 before the finger 28a and the member 28 engages respectively with the contacts 17 and 16. Since the line switch 15 always opens first to interrupt the circuit controlled by the accelerating switches 16 and 17, only the line switch 15 need be provided with the magnetic blowout 71, as shown in Fig. 1. At the same time the switch 18 closes to entirely short-circuit the field resistor R₃ and the switch 19 opens its lower contact and closes its upper contact to insure a strong initial energization of the upper portion of the operating electromagnet winding upon subsequent operation of the Start push button. Thus in the stopping position the several contacts of the motor controlling switch mechanism are in their relative positions shown in Figs. 1 and 3.

Upon the opening of the motor line switch

15, the dynamic braking circuit for the motor M is established automatically through the bottom contact of switch 15. The dynamic braking circuit includes the accelerating resistors R₁ and R₂, the motor armature and commutating field winding, as well as the braking relay 45. The full excitation of the shunt field, due to the short-circuiting of the resistor R₃, produces a strong braking action in the motor M. As long as the dynamic braking current of the motor M is of an appreciable value, the braking relay 45 functions to maintain its contact in the upper position thereby effectively preventing restarting of the motor M until the dynamic braking action of the motor is completed.

To restart the motor M, the start push button is closed. This results in energizing only the upper portion of the winding of the operating electromagnet 20, the circuit extending from the terminal 46 through the stop push button, the start push button, the upper contact of switch 19, to the intermediate terminal of the magnet winding, and thence through the contact of the braking relay 45 and the overload relay 44. In this way an excessive energizing current is supplied to the upper portion of the operating electromagnet winding and the movable armature 21 thereof is strongly attracted to the raised position. This results in the immediate operation of the contact operating member 24 to close the motor line switch 15, as shown in Fig. 4. Thereupon the motor M starts to accelerate with the current limiting resistors R₁ and R₂ in circuit therewith. At the same time the switch 19 is operated by the insulating finger 42 to open its upper contact and close its lower contact, thereby connecting all of the electromagnet winding in circuit and materially reducing the current input thereto.

The operation of the motor accelerating contacts 16 and 17 and the field reducing switch controlling finger 39, however, is retarded due to the engagement of the teeth of the curved rack gear 31 with the ratchet pinion 32, thereby setting up a strain in the several biasing springs 33, 34, and 40. This strain in the biasing springs results in movement of the rack gear 31 over the ratchet pinion 32 under the retarding influence of the timing pawl 58 and the retarding member 28 follows the movement of the contact operating member 24 to carry the accelerating contacts 16 and 17 to the closed position. As the retarding arm 28 moves under the strain of the biasing springs, the contact 16 first engages with its cooperating stationary contact 16', as indicated in Fig. 5. This results in short-circuiting the resistor R₁, thereby leaving only the resistor R₂ to limit the accelerating current of the motor. As the movement of the retarding arm 28 progresses further the contact 17 next is carried

into abutting engagement with its cooperating contact 17' to short-circuit the resistor R_2 , thereby removing all of the limiting resistance from the armature circuit of the 5 motor M. Upon further movement of the retarding member 28 the rack 31 runs free of the pinion 32. This results in a quick operation of the insulating finger 39 to open the field regulating switch 18, thereby inserting 10 the selected portion of the resistor R_3 in the motor field circuit. Thereupon the motor accelerates to its full running speed and the various elements of the starting mechanism again are in their respective positions in 15 which they are shown in Fig. 7.

Referring once more to Fig. 1 it will be observed that while all sides of the panel 12 are in close engagement with the sides of the enclosing casing 10, the four corners of the 20 panel base 12, upon which the motor starting switch mechanism is mounted are cut away. This facilitates the insertion of the necessary line and motor connections and control wiring through the conduit receiving 25 openings 70 located back of the panel 12 in the enclosing casing and the connection thereof to the proper terminals on the face of the panel 12. Since the resistors R_1 and R_2 are mounted directly upon the back of the panel 30 12, as shown in Fig. 2, to be removable as a unit therewith, and are directly connected with the proper acceleration and line contacts, it is possible to complete all of the wiring 35 connections directly upon the face of the panel 12. The cutting away of a portion of the panel 12 also serves to increase the facilities for ventilation. Magnetic arc blowout chutes 71 and 72 of the usual form are applied 40 respectively to the line switch 15 and the field switch 18 to quickly extinguish any arcs occurring upon the opening of these switches.

What I claim as new and desire to secure by Letters Patent of the United States, is,—

1. In a circuit controlling device, the combination of a plurality of contacts each movable from one circuit controlling position to a second circuit controlling position, an operating element movable quickly from one position to another, a separate spring connection 45 between each of said contacts and said operating element, sequencing means arranged in the paths of said contacts for causing said contacts to operate in a predetermined sequence, and a timing device for delaying the 50 operation of said contacts from said one circuit controlling position to said second controlling position when said operating element is moved quickly from one to the other of said positions.

60 2. In a circuit controlling device, the combination of a plurality of contacts, each movable from one circuit controlling position to a second circuit controlling position, an actuating element therefor operable from one 65 position to a second position, and having a

separate yielding connection with each contact, and a retarding element movable with a time delay action for setting up a strain in the yielding connections of said contacts upon operation of the actuating element between said positions and arranged to successively release the strains set up in said connections to effect operation of the contacts to said second position in a timed sequence. 70

3. In a circuit controlling device, the combination comprising an operating member quickly movable from one position to a second position, a plurality of contacts disposed in spaced relation with said operating member and yieldingly connected thereto to be operated from one circuit controlling position to a second circuit controlling position, and a retarding member interposed between the operating member and the said contacts and movable with a time delay action, said retarding member having parts out of alignment engaging said contacts to effect successive operation of the contacts to said second position in a timed sequence after a quick operation of said operating member between said 80 positions. 85

4. In a circuit controlling device, the combination of a plurality of contacts movable in substantially parallel paths from one circuit controlling position to a second circuit controlling position, a common actuating element therefor quickly operable from one position to a second position, a separate yielding connection between each contact and said actuating element comprising a compression spring, and time delay means having a common retarding element disposed in the paths of said contacts simultaneously to restrain operation thereof from said one circuit controlling position to thereby set up strains in 100 said compression springs upon a quick operation of the actuating element between said positions, the common retarding element of said time delay means having parts out of alignment engaging said contacts to successively release the strains of said compression springs and thereby effect operation of the contacts to said second circuit controlling position in a timed sequence. 105

5. A time element circuit controlling device 115 comprising a pivoted member having a plurality of relatively movable circuit controlling contacts mounted thereon to successively engage with cooperating contacts, an independently movable pivoted operating member having a yielding operating connection with said movable contacts, and time delay mechanism connected with said first pivoted member to insure engagement of the said movable contacts with the cooperating contacts in a timed sequence after operation of said operating member. 120

6. In a circuit controlling device, the combination with a quickly movable contact and a relatively movable contact operating mem- 125

ber, of a relatively movable contact retarding member interposed between the contact and the operating member, and an operating connection between the contact and the operating member extending through said retarding member and having a compression spring engaging the contact to be put under strain upon operation of the operating member away from the retarding member for operating the contact under the retarding action of the retarding member.

7. In a circuit controlling device, the combination of a plurality of contacts each operable from one circuit controlling position to a second circuit controlling position, a common operating electromagnet therefor having a movable magnetic member operatively connected through separate lost motion connections with a plurality of said contacts, and time delay means for retarding the taking up of the lost motion connections and having means for maintaining said plurality of contacts out of alignment to effect successive operation thereof to said second position in a timed sequence after unretarded operation of the said movable magnetic member to operate the remainder of the contacts to said second position.

8. A circuit controlling device comprising a pair of movable members, a yielding connection therebetween, a plurality of movable switch contacts, cooperating stationary contacts therefor, means for mounting a portion of the movable contacts on one of the said movable members in spaced relation to engage successively the cooperating stationary contacts upon operation of the other movable member between two positions and to disengage successively the cooperating contacts upon return operation of said other movable member, means for mounting one of the movable contacts on the said other pivoted member to engage the cooperating contact before the successive engagement of the said portion of the contacts and to disengage the cooperating contact before the successive disengagement of the said portion of the contacts, a time delay mechanism, and connections between the mechanism and the said one member for retarding the successive engagement of the contacts mounted thereon with the cooperating contacts and permitting unretarded disengagement thereof.

9. A circuit controlling device comprising a plurality of stationary contacts, a plurality of cooperating contacts, each movable into abutting engagement with a corresponding stationary contact, a common operating electromagnet for said movable contacts, a separate lost motion spring connection between the electromagnet and each of the movable contacts, and a time delay device for said contacts including a movable member associated with each of said spring connections for setting up a strain therein to move the member

upon operation of the electromagnet and provided with means for successively releasing the strains in said spring connections to effect operation of said movable contacts into abutting engagement with the stationary contacts in a timed sequence during the movement of the member.

10. A circuit controlling device comprising a pair of concentrically pivoted movable members disposed in overlapping relation, an electromagnet having a movable magnetic member connected with the first of said pivoted members to operate the same from one position to another position upon energization of the electromagnet, a time delay retarding mechanism connected with the second pivoted member through a one way driving connection, a plurality of relatively movable contacts, a plurality of cooperating contacts, different portions of the relatively movable contacts being mounted on each of said pivoted members with the contacts on the second pivoted member arranged in spaced relation to engage successively with the corresponding cooperating contacts, a separate yielding connection between the first pivoted member and each contact mounted on the second pivoted member for jointly setting up a strain to cause the second member to move under the retarding action of said retarding mechanism upon operation of the first pivoted member to said other position and thereby effect the successive engagement of the portion of the contacts mounted on the second pivoted member with the corresponding cooperating contacts in a timed sequence after the engagement of the portion of the contacts mounted on the first member with the corresponding cooperating contacts, and means for biasing said first and second members for simultaneous unretarded return movement to their initial positions upon deenergization of the electromagnet.

11. A controlling device for electric circuits comprising a line switch, a plurality of circuit controlling switches each having a separate resilient connection with the line switch, an operating electromagnet for the line switch, a time delay mechanism having a movable retarding member associated with said controlling switches for setting up strains in said resilient connections to operate the retarding member upon operation of the line switch by said electromagnet and sequencing means for successively releasing said strains during movement of said member to effect operation of said controlling switches in a timed sequence after operation of said line switch.

12. In combination with a controlling device for electric circuits provided with a line switch biased to an open position, a plurality of circuit controlling switches each biased to an open position, and a field controlling switch biased to the closed position, of an elec-

- tromagnet, an operating element moved by said electromagnet from one position to another, a separate spring connection between each of said switches and said operating element whereby said switches are operated by said element, sequencing means for causing said circuit controlling switches to close in a predetermined sequence and for causing said field switch to open after the closing of said circuit controlling switches, a timing mechanism for retarding the operation of said circuit controlling switches and said field switch, and means operated by said operating element for opening said line switch before corresponding operations of said other switches.
13. In a circuit controlling device, the combination of a switch member having two circuit closing positions and being biased to one of said positions, an electromagnet for operating the switch member to the other position, a plurality of cooperating switch members mechanically associated with the said first switch member to be biased thereby to one circuit controlling position and yieldingly connected with the said first switch member to be operated thereby to another circuit controlling position, and a time delay mechanism for insuring successive operation of the said cooperating switch members upon operation of said first switch to said other position and permitting substantially instantaneous operation of said cooperating switches upon operation of said first switch member to said one position in accordance with its bias.
14. In a circuit controlling device, the combination of a switch member operable between two circuit closing positions and being biased to one of said positions, an electromagnet for operating the switch member to the other circuit closing position, a plurality of cooperating switches mechanically connected with said first switch member to be operated simultaneously therewith upon operation of the first switch member to its biased position and yieldingly connected therewith for successive operation upon operation of said first switch member to said other circuit closing position, and a time delay mechanism connected with said cooperating switches for delaying successive operation thereof in a time sequence after operation of said first switch member upon energization of the electromagnet and permitting simultaneous operation thereof with said first switch member upon deenergization of the operating electromagnet.
15. A circuit controlling device comprising a line switch, a plurality of circuit controlling switches, means associated with said circuit controlling switches for causing said switches to operate in a predetermined sequence, an electromagnet, connections between said electromagnet and said line and circuit controlling switches for operating said switches, said connections including means for opening said line switch before the opening of said circuit controlling switches, and time delay means effective only during the closing of said circuit controlling switches for retarding the closing of said circuit controlling switches.

In witness whereof, I have hereunto set my hand this 9th day of February, 1927.

ROBERT W. GOFF.
